UNITED STATES PATENT OFFICE.

ERNEST L. BROOME, OF TARRYTOWN, NEW YORK.

DETACHABLE CIGAR BAND.

Application filed May 25, 1922. Serial No. 563,639.

To all whom it may concern:

Be it known that I, ERNEST L. BROOME, a citizen of the United States, residing at Tarrytown, in the county of Westchester 5 and State of New York, have invented a new and useful Detachable Cigar Band, of which the following is a specification.

The invention relates to a cigar band, and more particularly to detachable cigar bands 10 or the like.

The primary object of the invention is the provision of a band of this character, wherein in the band is fastened about the cigar with the use of a substance, such as paste or gum, 15 which is sensitive to heat at a low temperature, so that the heat which exists in the lighted cigar will cause the substance to melt, before the fire reaches the band, and the band to be detached or become automatically freed from the cigar, to the end that the wrapper of the cigar will not become damaged, which would result from the detachment of the said band by the fingers 20 of the hand of the smoker, as is usual.

There are various other objects and advantages of this invention besides the above and all of which will be hereinafter more fully or particularly brought out in the following specific description of the present 25 embodiment of the invention, the same being illustrated in the accompanying drawing, wherein:

Figure 1 is a perspective view of a cigar showing a band applied thereto in accordance with the invention;

Figure 2 is a view similar to Figure 1 with the ends of the band separated;

Figure 3 is an inner plan view of the band per se, showing the substance applied 40 to one end thereof.

Similar reference characters indicate corresponding parts throughout the several views in the drawing.

Referring to this drawing in detail, A 45 designates generally a cigar which is made in the usual manner and of any ordinary well known shape, and B the band which is usually made from paper and cut in any desirable shape. The band at one end thereof 50 has a coating 5 such as paraffin, gum, or other substance which is sensitive to heat and is adhesive, the end with the coating 5 being initially fastened to the other end of the band to secure it about the body

of the cigar A as is clearly shown in Figure 55 1 of the drawing.

When the cigar is lighted and being smoked, the heat from the burning end thereof will cause the heating of the substance 5 so as to melt such substance, thereby causing 10 the ends of the band to separate from each other, with the result that the band readily falls off of the cigar. It will be readily obvious that a band applied to the cigar in this manner will automatically free 15 itself when subjected to a moderate increase of heat, thereby avoiding the necessity of breaking or tearing the band from the cigar by the fingers of the smoker which is the usual method of detachment and frequently 20 breaks or damages the wrapper of the cigar.

From the foregoing, it is thought that the construction and manner of application of the invention will be clearly understood, and therefore a more extended explanation has 25 been omitted.

What is claimed is:—

1. The combination with a cigar, of a band, and a substance sensitive to heat at a low temperature for fastening the band 80 upon the cigar, said substance being melted when subjected to heat from the cigar when lighted.

2. A cigar band secured to the cigar by substance sensitive to heat, whereby the band 85 will become detached from the cigar when lighted in advance of the time that the fire reaches the band.

3. A cigar band having applied thereto a paste or gum by which it is secured on the 90 cigar, said paste or gum being sensitive to the heat of a lighted cigar, and permitting the said band to be freely detached in advance of the time that the fire reaches the band.

4. A cigar band having its meeting ends secured together by a paste or gum which is sensitive to the heat of a lighted cigar, and which will automatically free the band 100 from the cigar in advance of the fire reaching the band.

In testimony that I claim the foregoing as my own, I have hereto affixed my signature in the presence of two witnesses.

ERNEST L. BROOME.
